UNITED STATES PATENT OFFICE.

HOWARD W. PAYNTER, OF PHILADELPHIA, PENNSYLVANIA, ASSIGNOR OF ONE-HALF
TO HERBERT A. PAYNTER, OF PHILADELPHIA, PENNSYLVANIA.

TRANSPARENT LICENSE-TAG AND HOLDER.

1,238,936.

Specification of Letters Patent.

Patented Sept. 4, 1917.

Application filed April 18, 1916. Serial No. 91,916.

To all whom it may concern:

Be it known that I, HOWARD W. PAYNTER, a citizen of the United States, and a resident of Philadelphia, in the county of Philadelphia and State of Pennsylvania, have invented certain new and useful Improvements in Transparent License-Tags and Holders, of which the following is a specification.

10 This invention relates to improvements in transparent indicators and has for an object the production of a device which will indicate distinctly in daylight or at night the license numbers of vehicles, more particularly automobiles and comprises means for adapting the holder to display license tags of different sizes and one which can be readily cleaned and repaired.

With this and other objects in view my 20 invention consists in certain features of construction and arrangement of parts as will be hereinafter fully described and pointed out in the claims, reference being had to the accompanying drawing in which—

25 Figure 1 is a perspective view of my invention as it will appear in use.

Fig. 2 is a vertical section taken on line 2—2 of Fig. 3.

30 Fig. 3 is a horizontal section taken on line 3—3 of Fig. 2.

Fig. 4 is an enlarged vertical section.

Referring more particularly to the drawings 10 is a rectangular member open at one end and having at its opposite end a reduced and rounded prolongation 11 which has a circular forwardly projecting flange 12 which is threaded to receive a threaded ring 13 to hold a bull's eye 14 of suitable colored glass or other transparent or translucent material; the front of the member 10 is cut out and has the flanges 10^a and 10^b against which bears a plate of glass 15 to the rear face of which is applied an opaque sheet of celluloid or other suitable material 16 having cut out or stenciled the required characters 16^a to represent the number of the license, the year for which it is issued and the State issuing it. Across the back of the celluloid sheet 16 is applied a sheet 50 of preferably white material 17 sharply contrasting with the color of the celluloid sheet. Near the lower flange 10^b and secured to the upper and lower walls of the member 10 are the resilient strips or flanges 10^c and 55 10^d which bear against the back of the plate

bearing the license number and characters and holds it against the front face of the member 10; this strip 10^c also forms with the back of the member a channel 18 in which is slid a tubular conductor conduit 19 which is bent upwardly at 20 and then horizontally at 21 and carries at its extreme end a small electric incandescent bulb light 22 which projects into the prolongation 11 behind the bull's eye 14. At suitable points 60 in the pipe are T branches 23 carrying electric bulb lights 24 which will be behind the plate 15 so that the light may shine through the white paper or translucent backing and glass. The flange 10^c bears against the tubular conduit 19 holding it snugly in place against the back of the box and prevents 70 displacement or rattling.

A second member 25 rectangular in shape and having the front open and flanged at 75 25^a and 25^b telescopes over the open end of member 10 and has projecting through its closed end the nipple 26 which is threaded on and thus secured to the conductor pipe 19 the outer end of the thimble being enlarged or expanded at 26^a so that the electric conductor may pass freely to some suitable source of electricity appropriately located on the automobile. The closed end of member 25 has a continuous vertical strip of resilient material 27 secured to its inner face which bears against the backing of the plate and serves to hold the same firmly in place when the telescoping members are placed in proper juxtaposition. 85 90

Projecting from the rear walls of the casing are the threaded bolts 28 which are to be passed through openings in a bracket on the automobile to support the indicator and securely held thereto by nuts screwed on the 95 ends of the bolts, the bolts being unmovingly secured to the casing by upsetting the heads and by jam nuts.

The enlargement 26^a of the thimble 26 is for the purpose of allowing freedom of the 100 conductor wires and preventing their chafing or wear.

By placing the conductor wires in the tubing 19 they are protected against wear and from influence, by the weather and moisture 105 or dampness, and as the electric lights themselves are behind the transparent plate they are protected from accident.

Any suitable colored celluloid may be used and also any suitable paper or translucent 110

backing used, though I have found that dark brown celluloid and white backing produce highly satisfactory contrasting results which are equally efficacious in daylight or 5 at night.

It will be seen that I use few parts which are readily separable and detachable and that the device can be quickly cleaned and repaired such as replacing broken and worn 10 out bulbs and other parts which may become broken.

The flanges 10^a—10^b and the resilient strips 10^c and 25 securely, and at the same time yieldingly hold the glass plate in place 15 so that there is little or no danger of breakage from jar or jolting. Furthermore if the bulb which supplies light to the bull's eye becomes deficient in any way it can be readily removed and replaced by simply removing 20 the ring 13 and the bull's eye which can be done in a few seconds.

The parts all fit snugly and are weather tight so that the inner elements are not subject to atmospheric changes. By threading 25 the thimble 26 on the conduit 19, it is held in place and against longitudinal movement.

As the casing of the device consists of two telescopic members it is extensible and can 30 be made to fit any size character plate.

It will also be seen that I produce in one structure a combination tail light, sign or license plate and holder for the same.

I claim:—

35 1. A device of the character described, consisting of a casing comprising two separable telescoping members having aligned openings in the front faces thereof, one member having an interior resilient flange 40 projecting upwardly from its lower wall, and a tubular light conduit secured in the closed end of the second member, the aforesaid resilient flange serving the double function of holding a character sign plate against 45 the front wall of the casing and to hold the light conduit against the rear wall of the casing, said light conduit being removable from the casing with the second member.

50 2. A combination tail light, sign plate and holder, consisting of a telescopic casing formed of two telescoping members having vertical and horizontal front flanges, one member having upper and lower interior resilient horizontal flanges to hold a sign plate

against the front wall thereof and the other member having an interior resilient vertical flange to bear against one end of such plate, a transparent sign plate held by said flanges and a tubular light conductor conduit held within the casing and against the rear wall thereof by one of the aforesaid interior horizontal flanges.

3. A combination tail light, sign plate, and holder, consisting of a telescopic casing formed of two telescoping members, one 65 member having an integral prolongation at one end and a bull's eye carried thereby, the sign plate constituting approximately the front of the casing, an upstanding resilient flange within the longitudinal front end of 70 the casing, a tubular electric wire conduit mounted within the casing between the aforesaid resilient flange and the back wall, said conduit having illuminating means projecting therefrom behind the sign plate and 75 having one end bent to project to the rear of the bull's eye, a thimble secured to the end of the second member of the casing and projecting from said member, said thimble having an enlarged diameter at its free end to 80 permit freedom of movement of an electric conductor carried by the conduit.

4. A combined tail light sign plate and holder consisting of a telescopic casing formed of two telescoping members, one 85 member having continuous resilient interior horizontal flanges, and the other member having a continuous resilient interior vertical flange and illuminating means within the casing resiliently held against the back of 90 the casing by one of the horizontal resilient flanges, and said resilient flanges also yieldingly holding the sign plate in position against the front face of the casing.

5. A combined tail light, sign plate, and 95 light holder, comprising a casing consisting of two telescoping members having aligned openings in their front faces, one member having upper and lower horizontally disposed interior flexible flanges, and the other 100 member having a vertical interior flexible flange, a light carrying conduit held between one of the said horizontally disposed flanges and the rear wall of the casing, and a sign plate held against the front of the 105 casing by said flexible flanges.

HOWARD W. PAYNTER.
